HAT REST

Reginald D. Osgoodby, Evanston, Ill.

Application July 30, 1953, Serial No. 371,369

3 Claims. (Cl. 211—33)

This invention relates to a hat rest. The invention is particularly useful in the supporting of hats provided with brims whereby said brims are supported above the surfaces upon which the hat rest stands.

It is common to support hats upon various types of supports such as hooks, shelves, and various other types of supports. With such structures, however, there is a tendency for the brim of the hat to strike the shelf or to strike the wall upon which the hook is placed, so that the brim thus loses its attractive curvature and the hat becomes distorted in appearance. Further, the supports engage only a portion of the hat and there is a tendency for the engaged portion to become distorted at the point of engagement. There has long been a need for a hat support which would uniformly engage the hat about the inner band portion thereof so as to prevent distortion of the hat while at the same time protecting the brim from engagement with any surface and while also providing ventilation for the interior of the hat.

An object of the present invention is to provide a hat structure overcoming the above described disadvantages and providing the new results sought. A further object is to provide a support which not only furnishes a uniform support for the hat portion along the inner band thereof but also provides ventilation for the inner surface of the hat and provides a compartment therein for receiving gloves, handkerchiefs, scarves, and the like. A still further object is to provide a hat rest of a novel design having new advantages. Other specific objects and advantages will appear as the specification proceeds.

The invention is shown, in an illustrative embodiment, by the accompanying drawings, in which—

Figure 1 is a perspective view of a hat rest embodying my invention and showing a hat supported thereon; Fig. 2, a top plan view of the hat rest with the hat removed; Fig. 3, a bottom plan view; Fig. 4, a broken, part-sectional view, the section being taken as indicated at line 4—4 of Fig. 3; Fig. 5, a top plan view of a modified form of hat rest embodying my invention; and Fig. 6, a sectional view, the section being taken as indicated at line 6—6 of Fig. 5.

In the illustration given, 10 designates a hat having a brim 11 turned downwardly at its forward end to provide a smoothly-formed, shaped brim. When such a hat is placed upon a shelf, it is found that the brim is pressed upwardly to form a crease along the forward, downwardly-curved portion 11, and that it is thereafter difficult to obtain the desired smooth curvature illustrated in Fig. 1. Further, when such a hat is placed upon a hook or support having a portion engaging the upper inner portion of the crown, a deformation of that portion of the crown is obtained which is later difficult to remove.

The hat rest 12 indicated in the drawings may be formed of plastic, metal, molding materials, composition materials, and a plurality of other suitable materials. In the illustration given, there is formed an outer inclined wall 13 having slots or windows 14 therein, and below the inclined wall portion 13 extends a base 15 providing

2

an annular ledge 16. The base 15 is scalloped or provided with a plurality of air vents 17 so that when the base rests upon a surface, air may flow freely into the interior of the rest.

5 Near its top, the inclined wall 13 meets an inwardly-inclined wall 18 which extends downwardly and inwardly to merge with a bottom wall 19. The bottom wall 19 is preferably perforated, as indicated by the numeral 20.

In the operation of the structure, the hat rest may 10 be placed upon a shelf or other supporting surface and then a hat 10 may be placed thereon. By reason of the inclined wall 13, the rest is adapted to receive a large number of hats of varying sizes. The hat is engaged only at the inner band, which thus offers protection at the point 15 where the hat is engaged, so that no distortion of the crown or the brim can take place. In the event that the band is covered by perspiration, ventilation for the evaporation of the perspiration is afforded through the inclined slanting windows or slots 14 and circulation of 20 air can take place not only through such windows or slots, but also through the base apertures 17 and through the apertures 20. No point of the crown and no point on the brim of the hat is engaged by the rest, the contact 25 between the rest and the hat being limited to the reinforced band portion on the interior of the hat. The shape of the crown and the shape of the brim are thus not marred or interfered with during the supporting of the hat on the rest.

Within the compartment provided by the walls 18 and 30 19 on the interior of the rest may be placed gloves, scarves, handkerchiefs and other articles, and these are spaced inwardly from the hat band by the inwardly-inclined solid wall 18 of the rest. The hat itself, when supported upon the rest, provides the cover for the compartment.

35 If desired, the compartment or box 18 may be formed integrally with the wall 13, or the two structures may be formed separately and may be separated by an inclined wall 21, as shown more clearly in Fig. 4. If the division line 21 is provided, the inner box may be lifted out and 40 the structure may be used without the box 18 being employed. As above stated, the inner box 18 may, if desired, be formed integrally with the wall 13 so that there is but one single unitary structure.

In the modification shown in Figs. 5 and 6, I provide 45 an inner wall 22 which is somewhat elliptical in shape and provided with a bottom wall 23 having open spaces 24 therein. Such a structure provides a compartment useful for holding gloves, scarves, handkerchiefs, and other objects. The upper portion of wall 22 is turned 50 downwardly and outwardly to provide a hat-supporting rest 24a. The wall 24a may be turned outwardly at its bottom to provide a horizontal ledge 25. I prefer to provide the rest 24a with a number of slots or ventilation openings 26.

55 The bottom wall 23 of the structure may be equipped with spaced legs 27 providing a base for supporting the hat rest upon a shelf or other surface. I also prefer to provide the flange 25 with a pair of spaced knobs or studs 28 which are engageable with the bracket for supporting the rest from a wall, if it is desired to have a wall support for the rest. I also provide the inner wall 22 with vertically-extending slots 29. Thus when the structure is in a supporting position for receiving a hat, air may circulate through the outer inclined wall 24a and 60 also through the inner wall 29, thus furnishing communicating air currents to every portion of the hat.

While, in the foregoing specification, I have set forth specific structures in considerable detail for the purpose of illustrating an embodiment of the invention, it will be 65 understood that such details of structure may be varied widely by those skilled in the art without departing from the spirit of my invention.

I claim:

1. A hat rest device, comprising a base and an oval wall carried thereby extending upwardly and then curved downwardly and outwardly to provide a flared hat-supporting flange, said flared outwardly supporting flange terminating in a horizontal flange spaced vertically and laterally from said base, said hat-supporting flange being provided throughout with spaced apertures for the circulation of air therethrough, and a platform connecting the oval wall supported by said base.

2. A hat rest device, comprising a base, a perforated platform carried by said base, a wall extending upwardly from said platform to provide a generally vertical inner wall and then extending downwardly and outwardly to provide an inclined outer wall providing a support adapted to be engaged by the band of a hat, said outer wall and said inner wall being provided with spaced apertures for the circulation of air therethrough and said outer wall terminating at a point spaced above said base.

3. A hat rest device, comprising a molded, generally

10

15

20

oval body provided with a base having apertures therethrough, a hat rest wall supported by said base and being in the form of an inverted V, the outer wall of said support being inclined outwardly and downwardly and provided with apertures, and said inner wall being provided with an apertured bottom spaced upwardly from the bottom of said base.
